UNITED STATES PATENT OFFICE.

FREDERICK W. JUDD, OF CLEVELAND, OHIO, ASSIGNOR TO THE WROUGHT IRON RANGE COMPANY, OF ST. LOUIS, MISSOURI, A CORPORATION OF MISSOURI.

DESIGN FOR A RESERVOIR-TOP.

42,140.

Specification for Design.

Patented Feb. 6, 1912.

Application filed November 25, 1908. Serial No. 464,504. Term of patent 7 years.

To all whom it may concern:

Be it known that I, FREDERICK W. JUDD, a citizen of the United States, residing at Cleveland, in the county of Cuyahoga and State of Ohio, have invented a new, original, and ornamental Design for a Reservoir-Top, of which the following is a specification, reference being had to the accompanying drawing, forming a part thereof.

The drawing is a perspective view of the reservoir top.

I claim:

The ornamental design for a reservoir top, as shown.

FREDERICK W. JUDD.

Witnesses:

H. R. SULLIVAN,
E. L. THURSTON.
